UNITED STATES PATENT OFFICE.

GEORGE NEUMANN, OF CHICAGO, ILLINOIS.

EMBOSSING-GAGE.

1,349,579.

Specification of Letters Patent. Patented Aug. 17, 1920.

Application filed October 1, 1919. Serial No. 327,808.

To all whom it may concern:

Be it known that I, GEORGE NEUMANN, a citizen of the United States, residing at Chicago, in the county of Cook and State 5 of Illinois, have invented a certain new and useful Improvement in Embossing-Gages, of which the following is a specification.

My invention relates to embossing gages and has for its purpose to provide a gage for 10 use with hand or power embossing presses, which will insure a uniform placing of the paper stock embossed therein.

I illustrate my invention more or less 15 diagrammatically in the following drawings wherein:

Figure 1 is a view of the upper surface of my gage;

Fig. 2 is a side elevation of my gage in place in the embossing press;

Fig. 3 is a section on the line 3—3 of 20 Fig. 1;

Fig. 4 is a section on the line 4—4 of Fig. 1;

Fig. 5 is an end elevation of the two parts 25 of the stop removed from the plate;

Fig. 6 is an alternative form of stop used with my gage.

Like parts are illustrated by like numbers and letters in all the figures.

A is a flat plate preferably of nickel-plated metal, but of any suitable material which can take a smooth hard surface. It is beveled off as at B on the side adjacent the press C with which it is used, and for which 35 it holds the paper stock illustrated as C¹ in Fig. 2. Parallel with the beveled edge are the slots D. These slots are arranged in two groups, one at each end of the plate, which are separated by a group of narrower slots

40 E perpendicular thereto. The edges of all the slots are rounded or beveled as at E¹. I have illustrated four of these centrally disposed slots although the number might be varied. Interrupted by the slots D are other

45 slots F parallel to the slots E with similar rounded or beveled edges. The lower surface G of the plate is flat. The slots all open into grooves G¹ on the lower surface, which run parallel with the slots, but are of considerably greater width. Some or all of the slots may be lined with graduated marks as at G², to assist in the accurate adjustment of stops H which ride in the slots. Each stop is composed of an upper stop member

50 H¹ with an upwardly and outwardly extend-

ing flange H² at the upper edge of its forward face. The lower surface of H¹ forms a ridge H³ adapted to penetrate the slot. The stop is pierced to receive a thumb screw H⁴ which passes through the slot and penetrates a nut H⁵ adapted to lie within the grooves G¹ on the under side of the plate. The lower surface of the nut is substantially flush with the lower surface of the plate and its upper surface is formed with the 60 projection H⁶, which penetrates the slot. I is a variant form of stop, with a long flange I¹ upwardly and forwardly inclined from its forward face.

J is a securing means illustrated as a 70 spring finger, whereby the plate A is adjustably secured to the press. Its shape and length may be varied, and a plurality of such securing means may be used, the requirement being that they yieldingly secure the 75 plate A to the press permitting adjustment.

It will be understood that I might greatly vary the shape, proportion and relation of all the parts without departing from the spirit of my invention. In particular, the 80 arrangement of slots which I have illustrated may be almost infinitely varied. The number may be changed and the spatial relations of the longitudinal and transversal slots. The details of the stop may also be 85 greatly changed, the salient feature of the invention as a whole, being the adjustment of a plurality of paper engaging stops, some on longitudinal and others on transversal axes on a flat plate. I do not limit myself 90 to the specific means of adjustment illustrated.

The use and operation of my invention are as follows:

It is present practice to hold the stock in 95 place by means of pins or slugs which are pinned in or sealed on a card-board placed in front of the press. These are difficult of adjustment and almost impossible of accurate adjustment, all adjustment being a matter of guess work. When the pins or slugs are not accurately adjusted, the stock will be badly centered, and the embossing out of place. Furthermore the pins, which are most commonly used, cut the edges of the paper 100 stock, particularly when thin stock is used, and thus both injure the stock and impair the placing. The card-board in which the pins are placed and to which the slugs are sealed with sealing wax, must be replaced 105 110

continually, since it rapidly wears out, or is injured by the application and removal of pins or slugs. This waste of stock and cardboard involves a considerable loss, to which must be added the waste in operating time required to make the clumsy adjustments.

The plate is clamped in place on the embossing press by such means as are commonly furnished in such presses for holding the card-board earlier mentioned. Two stops are ordinarily used on the set of slots perpendicular to the press. They support the bottom of the stock, and must be accurately adjusted with relation to each other. The graduated marks on the slots makes this easy. The broad slots horizontal to the press provide for a single stop used to hold the edge of the stock. The slots on one side of the plate will be used for right hand feeding and those on the other side for left hand feeding.

The paper to be fed into the machine is simply placed on the plate, the bottom of the paper being supported in place by the two lugs adjusted along perpendicular slots, and the side of the paper being positioned by the stop in the horizontal slot. The graduated marks along the slots enable the operator to make the setting of the two lower lugs uniform, provided the gage plate is accurately lined with the work. The graduated marks will enable the operator to repeat the setting of earlier runs of work provided he makes a notation of the setting at that time.

When small stock is being used the stops on the perpendicular slots can be pushed up almost to the beveled forward edge of the plate, and the lateral stop on the upper horizontal slot will be used. The gage is prepared for large stock by placing the stops on the perpendicular slots along the outer edge of the gage and by moving the lateral stop to the lower horizontal slot. Obviously a considerable number of stops might be used, being kept at the extremities of the slots to obviate the necessity of moving the stops from slot to slot, but in practice three or four stops are found to be enough.

The beveling of the forward edge of the gage prevents indentation of the stock by the edge of the plate. The beveling of the edges of all the slots obviates the risk of the edges or corners of the stock catching or bending or tearing. The slots further provide space for insertion of the finger tips to lift the stock from the gage when the work is completed, or shift it on the gage when that is necessary.

The flange or ridge on the lower surface of the stops prevents the stock from slipping in under the stop member.

I have illustrated an alternative form of stop, with a long upwardly inclined flange upon its forward face. This stop is adapted

to receive stock whose edges tend to curl up. The outer tip of the flange is considerably higher above the gage than the base of the flange, and the curled edges are not so likely to pass over it as they are in the other form of stop.

The nuts which ride in the grooves on the lower side of the gage are flush with the bottom of the gage. It is thus possible to shift the stops on the gage without removing the gage from the surface on which it rests. Thus the gage may be kept securely fastened to the press during adjustment of the stops thereon.

I claim:

1. An embossing gage adapted to be removably and adjustably attached to an embossing press, adjacent the embossing stamp thereof, comprising a flat plate and means for securing it to the press, the side adjacent the stamp being beveled, said plate penetrated by a plurality of slots, some parallel with the beveled edge, and others perpendicular to it, a central group of the perpendicular slots continuing unbroken substantially across the plate, the remainder intercepted by the horizontal slots.

2. An embossing gage adapted to be removably and adjustably attached to an embossing press, adjacent the embossing stamp thereof, comprising a flat plate and means for securing it to the press, the side adjacent the stamp being beveled, said plate penetrated by a plurality of slots, some parallel with the beveled edge, and others perpendicular to it, a central group of the perpendicular slots continuing unbroken substantially across the plate, the remainder intercepted by the horizontal slots, adjacent the beveled edge.

3. An embossing gage adapted to be removably and adjustably attached to an embossing press adjacent the embossing stamp, comprising a flat plate and means for securing it to the press, the side adjacent the stamp being beveled, said plate pierced by a plurality of slots, and stops adapted to be adjusted along said slots, each comprising an upper stop member, a longitudinal lug on the bottom of said member adapted to penetrate the slot, a nut engaging the bottom of the plate and means to lock the stop and nut together against the plate.

4. An embossing gage adapted to be removably and adjustably attached to an embossing press, adjacent the embossing stamp, comprising a flat plate pierced by a plurality of slots and means for securing it to the press, the side adjacent the stamp being beveled, the lower surface of the plate broken by grooves broader than said slots, into which said slots open, a plurality of stops adapted adjustably to be secured in said slots, each comprising an upper stop member with a forwardly projecting lip on

the upper edge of its face, a longitudinal lug on the bottom of the stop adapted to penetrate the slot, a thumb screw penetrating the stop, a nut engaged thereby, said nut shaped to fit within the groove and lie flush with the lower surface of the plate.

5. A gage adapted to be removably and adjustably attached to a press, adjacent the stamp of said press, comprising a quadrilateral flat plate and means for securing it to the press, said plate pierced by a plurality of slots, some of said slots being parallel with the edge of the plate adjacent the stamp, others being perpendicular thereto, a 10 plurality of said perpendicular slots being intercepted and divided by said horizontal slots, said horizontal slots being intercepted and divided by a central group of vertical slots, and stops adapted to be adjusted along said slots.
- 15 6. A gage adapted to be removably and

adjustably attached to a press, adjacent the stamp of said press, comprising a quadrilateral flat plate and means for securing it to the press, said plate pierced by a plurality of slots, some of said slots being parallel 25 with the edge of the plate adjacent the stamp, others being perpendicular thereto, a plurality of said perpendicular slots being intercepted and divided by said horizontal slots, said horizontal slots being intercepted 30 and divided by a central group of vertical slots, and stops adapted to be adjusted along said slots.

In testimony whereof I affix my signature, in the presence of two witnesses, this 24th 35 day of September, 1919.

GEORGE NEUMANN.
